UNITED STATES PATENT OFFICE

2,546,797

HOLDER FOR GARBAGE CONTAINERS

Joseph R. Swisher and James A. Soules,
Decatur, Ill.

Application March 13, 1948, Serial No. 14,678

2 Claims. (Cl. 248—311)

1

This invention relates to garbage pail holders and more particularly to such that can be mounted on a wall, fence or an upright post or other suitable support.

An important object of the invention is to simplify the construction so as to facilitate its manufacture and minimize the cost thereof, and at the same time produce a device of its kind which is easily kept clean, is especially sanitary on the whole and is practical and highly efficient for the purpose intended. With these and other objects and advantages to be attained, as will hereinafter more fully appear in the following description, the invention consists in the parts and combinations and arrangement of parts described in connection with the accompanying drawings illustrative of a practical but non-limiting adaptation of the invention.

In the drawings:

Figure 1 is a side elevational view of the holder device with a conventional garbage pail placed thereon, the holder device being shown in full lines and the pail in dotted lines.

Figure 2 is a front elevational view of the parts shown in Figure 1;

Figure 3 is a top plan view;

Figure 4 is a detail perspective view of the horizontal supporting base member of the holder device alone and detached from the frame structure; and

Figure 5 is a detail perspective view of one of the transverse support members that are provided on the horizontal supporting base member in the complete frame assembly of the holder device.

Referring now to the drawings in detail, the numeral 6 designates an elongated, relatively narrow, upright bar which is apertured at intervals lengthwise thereof, as at 1, so as to receive securing screws or bolts (not shown) by which the bar can be fastened securely to a wall, fence or a post or other support. To secure lightness with ample rigidity and strength in the bar 6 it is shown as marginally flanged throughout its longitudinal sides and ends, thus making it flat-faced on its outer side and hollow on its inner side, with its marginal stiffening flanges disposed inwardly so as to abut the face of the wall, fence, posts or the like to which the bar is attached in use of the holder device.

Bolted, as at 8, or otherwise securely and rigidly fastened to the lower portion of said bar 6, is a horizontal supporting base or bracket member 9. This member 9, as shown, is in the form of a rigid cast metal frame having a rectangular margin-

2

ally flanged and vertically channeled socket portion 10 which fits over the aforesaid upright bar member 6 and is provided with an aperture 11 to register with a corresponding aperture obviously provided in the bar member to receive the securing bolt 8 just above described.

The supporting base or bracket member 9, as shown, comprises two outer side rails 12 extending outward from the socket portion 10 and cross-connected near their outer ends by a transverse bar 13, said side rails 12 having upturned outer end portions 14. The transverse bar 13 is rigidly connected to the socket portion 10 by a medial longitudinal bar 15, said medial bar 15 having a triangular gusset portion or reinforcing rib 16 on its underside. The inner end 17 of this portion 16 is squared and abuts the adjacent lower, outer face portion of the upright main frame bar 6 of the holder device (see Figures 1 and 2).

Obviously, the open frame-like supporting base element 9 is, in itself, rigid, and the peculiarly marginally flanged and channeled attaching provision of the socket portion 10, together with the particular end abutment 17 of the medial bar 15 reinforcement 16, makes for lightness of structure of the element and strength and steadiness in its attachment to said upright main frame bar 6. This is of particular advantage because said supporting base element 9 has to carry the weight of the garbage pail whether the same be loaded or unloaded.

In Figures 1, 2 and 3, the garbage pail is designated by the numeral 18 as in place on the holder device and it is illustrated in dotted lines. As shown, the base element 9 (see Figure 1) is of a length to extend diametrically under and project slightly beyond the pail 18 and the upturned ends 14 of the side rails 12 of said element 9 serve as stops to normally prevent the pail 18 from sliding off said element 9.

To support the cover 19 of pail 18 when removed from the pail a chain or other suitable flexible element of cord 20 is fastened at one end to the upper end portion of the upright main frame bar 6 of the holder device, as at 21, the other end of the element 20 being attached, as at 22, to the handle loop 23 of said cover 19. In this way the cover 19 can be obviously removed from the pail 18 at will and allowed to hang by the chain or flexible supporting element 20 whenever access to the pail 18 is desired or it becomes necessary to remove the pail from the holder device.

Adequate provision for supplemental transverse support of the pail 18 on the base element 9 is

added by a pair of oppositely laterally projected L-shaped members 24. One leg of each member 24 is horizontally disposed and supportedly attached on the base element 9, with the upstanding other leg 25 of the member 24 in a position a distance laterally from said element 9 so as to serve as a retainer at that side of the pail, while the oppositely extended horizontal leg portions of the two members 24 serve to support the pail 18 so as to prevent tipping of the pail at either side of said base element 9.

Preferably, the attachment of the members 24 is adjustable on the base element 9. As shown (see Figure 4) the two side rails 12 and medial bar 15 of the element 9 are recessed, as at 26, to provide seats in which the laterally overlapped horizontal legs of the members 24 are fitted horizontally slideable. As shown, the recessed seat portion 26 of the medial bar 15 of the element 9 is widened and provided with a pair of screw-threaded apertures 27 to receive securing screws 28 (see Figure 3) that are passed through longitudinal slots 29 provided therefor in the companion horizontal leg portions of the member 24. In this way the members 24 can be obviously adjusted transversely of the base element 9 and fastened by the screws 28 in such adjusted position.

From the foregoing, it is apparent that a simple yet practical and efficient, sanitary holder device for garbage pails is provided, on which the pail is stably supported with minimum liability of accidental dumping thereon and yet the pail is readily placed upon and removed from the holder device at will.

Obviously, while the illustrated structure is that of a practical adaptation of the invention, the same is not in limitation specifically thereto, as modification and change is possible, and contemplated within the scope of the appended claims.

What is claimed is:

1. A holder device for garbage pails and the like, the same comprising a rigid, open, frame-like support including an upright bar for attachment to a wall face or other vertical supporting surface, a horizontal base element attached at its inner end to the lower portion of said upright bar and having upturned pail retainer provision at its outer end, and a pair of transverse supplemental supporting members of substantially L-shape and respectively mounted with one of their legs horizontal and secured in side by side

relation with provision for relative longitudinal adjustment cross-wise on said horizontal base element and their other legs vertical and disposed laterally from opposite sides of the base element.

2. The herein described holder device for garbage pails and the like, comprising an upright bar for attachment to a supporting wall face or the like, said bar being marginally flanged rearwardly and having a flat front face, an open frame-like horizontal base element having a vertically channelled socket portion at its inner end attached to the lower portion of said upright bar, a pair of transversely spaced apart longitudinal side rails extending forward from said socket portion with upturned outer ends and cross-connected near said ends, a medial longitudinal bar connecting said socket portion with the cross-connection between said side rails and having a depending, longitudinal, reinforcing rib the inner end of which is squared and abuts the adjacent outer face portion of said upright bar, said side rails and medial longitudinal bar being recessed in transverse alignment, and a pair of L-shape supporting members with one leg of each upstanding and projected laterally from the base element and the outer legs of said supporting members horizontal in side-by-side relation to each other and seated slidably adjustable in the recessed portions of said base element, the horizontal legs of said L-shape supporting members having longitudinal slots through which releasable fasteners are inserted and held in apertures provided in the recessed portions of the base element.

JOSEPH R. SWISHER.
